UNITED STATES PATENT OFFICE.

GEORGE A. MEAD, OF MANSFIELD, OHIO.

RAIL-BOND.

No. 846,122.

Specification of Letters Patent.

Patented March 5, 1907.

Application filed November 23, 1904. Serial No. 233,937.

To all whom it may concern:

Be it known that I, GEORGE A. MEAD, a citizen of the United States, residing at Mansfield, in the county of Richland and State of Ohio, have invented a new and useful Rail-Bond, of which the following is a specification.

This invention relates to rail-bonds.

The object of the invention is to provide means for efficiently securing rail-bond terminals to the surfaces of rails or other parts to be bonded.

Other objects of the invention will appear more fully hereinafter.

15 The invention consists, substantially, in the construction, combination, location, and arrangement of parts, all as will be more fully hereinafter set forth, as shown in the accompanying drawing, and finally pointed out in 20 the appended claims.

Referring to the accompanying drawing and to the various views and reference-signs appearing thereon; Figure 1 is a view in perspective of a rail-bond, showing the application thereto of a detachable solder-strip in accordance with the principles of my invention. Fig. 2 is a transverse section of the same. Figs. 3, 4, and 5 are views similar to Fig. 2, showing modified forms of solder-30 strips embraced within the spirit and scope of my invention.

In the application of rail-bonds, and particularly rail-bonds provided with flat terminal feet or terminals having flat surfaces, 35 to the surfaces of rails or other parts to be bonded it is a common practice to solder such surfaces. It has heretofore been proposed to provide rail-bonds of this class and type with permanent coatings and strips of 40 solder applied to the surface of the bond-terminal which is to be applied to the rail or other part to be bonded. The objection to this practice is that the purchaser of a bond is required to pay also for the additional 45 solder-strip, which is permanently attached thereto and forms part of the same, whereas it frequently happens that the use of a solder-strip is not desired in order to apply the bond-terminal to the surface to be bonded, 50 thereby resulting in an increased cost and expense to the purchaser of the bond.

It is the special purpose of my present invention to provide a detachable solder-strip for rail-bonds and for application to the terminals thereof, which may be supplied with 55

the bonds or independently of the bonds, and which may be placed in position against the bond-terminal surface when the use of such solder-strip is desired, but which may be omitted when the use of such solder is not required, the essential feature being an independent detachable solder-strip.

Referring to the accompanying drawing, reference-sign A designates a rail-bond, which may be of any suitable type or construction and having flat terminals B to be applied to the surface of the rail or other part to be bonded.

C designates a detachable solder-strip. This solder-strip may be in any suitable or 70 desired form. For instance and as shown at C in Fig. 4 it may be in the form of a flat strip adapted to be applied flatwise against the surface of the bond-terminal, which is to be applied to the rail or other part to be 75 bonded and between the surfaces of the bond-terminal and rail when required for use. If desired and in order to afford means for supporting the solder-strip upon the bond-terminal while the bond is being placed 80 in position for application to the rail or other part to be bonded, the solder-strip C² (see Fig. 3) may be provided with an angular flange D, arranged to engage over the upper edge of the bond-terminal, whereby the solder-strip is suspended or supported by the terminal. In Figs. 1 and 2 I have shown the solder-strip C of channel shape, that is provided with flanges D', the body of the bond-terminal being received in the channel 90 formed thereby, thus affording means for supporting the solder-strip upon the bond-terminal. In Fig. 5 I have shown a modified form of solder-strip C³, provided with lateral flanges D², arranged to fit over the 95 edges of the bond-terminal, said flanges terminating in overturned portions E to engage the outer surfaces of the bond-terminal. In any case it will be seen that the solder-strip is detachable, and hence can be readily removed when not required; but when required it may be threaded upon the terminal and placed in position against the surface thereof which is to be applied to the surface of the rail or other part to be bonded and 105 which, if desired, may be suspended or supported by the bond-terminal while the bond is being handled or applied to the rail-surface.

As above indicated the particular type or 110

construction of rail-bond is immaterial so far as my invention is concerned, so long as it is provided with terminals for application to the rail or other part to be bonded. It is also obvious that the solder-strips may be varied in shape or cross-section and may or may not be provided with means for suspending or supporting the same upon the bond-terminal, and the form or construction of such strip to enable the same to be suspended or supported upon the terminal may be varied without departure from the spirit and scope of my invention, the essential feature of which, as above indicated, is in the provision of a solder-strip which may be detached from or applied to the bond at will. In practice the solder-strips are of somewhat less length than the bond-terminal to which the same is to be applied, though this is not an essential feature of the invention.

Having now set forth the object and nature of my invention and a construction embodying the principles thereof, what I claim

as new and useful and of my own invention, and desire to secure by Letters Patent, is—

1. The combination of a rail-bond having a terminal, of a longitudinally-removable solder-strip provided with retaining-flanges at the edges thereof to engage over the edges of the bond-terminal.

2. The combination with a rail-bond having terminals, of a solder-strip adapted to be removably applied to one surface of the bond-terminal and having flanges engaging over the edges of the terminal of the bond, said flanges having turned-over portions to engage the other surface of the bond-terminal.

In witness whereof I have hereunto set my hand, this 19th day of November, 1904, in the presence of the subscribing witnesses.

GEORGE A. MEAD.
